CLAIM

I hereby claim the ornamental design for a socket, as shown and described.

DESCRIPTION

FIG. 1 is a perspective view of a socket in accordance with the preferred embodiment of the present invention, showing my design;

FIG. 2 is a front view of the socket shown in FIG. 1;

FIG. 3 is a rear view of the socket shown in FIG. 1;

FIG. 4 is a left side view of the socket shown in FIG. 1;

FIG. 5 is a right side view of the socket shown in FIG. 1;

FIG. 6 is a top view of the socket shown in FIG. 1;

FIG. 7 is a bottom view of the socket shown in FIG. 1; and,

FIG. 8 is a cross-sectional view of the socket shown in FIG. 1.
